US00D865337S

(12) **United States Design Patent** (10) **Patent No.:** **US D865,337 S**
(45) **Date of Patent:** **** Nov. 5, 2019**

(54) **FOOTWEAR**

(71) Applicant: **Crocs, Inc.**, Niwot, CO (US)

(72) Inventor: **Daniel S. Laska**, Lyons, CO (US)

(73) Assignee: **CROCS, INC.**, Niwot, CO (US)

(**) Term: **15 Years**

(21) Appl. No.: **29/669,908**

(22) Filed: **Nov. 12, 2018**

Related U.S. Application Data

(63) Continuation of application No. 29/554,122, filed on Feb. 8, 2016, now Pat. No. Des. 833,126.

(51) **LOC (12) Cl.** **02-04**

(52) **U.S. Cl.**

USPC **D2/907**

(58) **Field of Classification Search**

USPC D2/907

(57) **CLAIM**

The ornamental design for footwear, as shown and described.

DESCRIPTION

FIG. 1 is a front perspective view of footwear;

FIG. 2 is a front view thereof;

FIG. 3 is a back view thereof;

FIG. 4 is a right side elevational view thereof;

FIG. 5 is a left side elevational view thereof;

FIG. 6 is a top view thereof; and,

FIG. 7 is a bottom view thereof.

In the drawings, the broken lines depict environmental subject matter only and form no part of the claimed design.

1 Claim, 7 Drawing Sheets
